BOOSTER ACTUATING MECHANISM FOR PRESSING MACHINES

Filed April 25, 1929 2 Sheets-Sheet 2

UNITED STATES PATENT OFFICE

ERNEST DAVIS, OF SYRACUSE, NEW YORK, ASSIGNOR TO THE PROSPERITY COMPANY, INC., OF SYRACUSE, NEW YORK, A CORPORATION OF NEW YORK

BOOSTER ACTUATING MECHANISM FOR PRESSING MACHINES

Application filed April 25, 1929. Serial No. 358,142.

This invention relates to pressing machines, as garment and laundry pressing machines, and has for its object a particularly simple and efficient actuating mechanism therefor, by which a practically uniform pressure is delivered regardless of the thickness of the work or the padding on one or both pressing elements, and regardless of the amount of compression the padding undergoes within limits during the pressing operation.

The invention consists in the novel features and in the combinations and constructions hereinafter set forth and claimed.

In describing this invention, reference is had to the accompanying drawings in which like characters designate corresponding parts in all the views.

Figure 1 is a side elevation, partly broken away, of a pressing machine embodying my invention.

Figure 2 is an enlarged fragmentary sectional view, taken approximately on line 2-2, Figure 1.

Figure 3 is an elevation of parts seen in Figure 2.

Figure 4 is an enlarged fragmentary sectional view on line 4-4, Figure 1.

Figure 5 is a detail view, partly broken away, of the detent for holding the cam from rotation until the toggle straightens.

The invention comprises, generally, a toggle and connections between a prime mover or the actuator and the toggle to successively straighten the toggle and lengthen one of the links thereof or boost the toggle during the closing of the press, and also means operated by the boosting movement to hold the links from further pivotal movement, that is, hold them in any one of an indefinite number of positions that they may assume when the movable pressing element encounters the work on the other pressing element of the machine.

I have here illustrated my invention as embodied in the conventional type of pressing machine comprising a stationary pressing element or buck 1 and a movable pressing element or head 2 movable toward and from the buck. The buck 1 is mounted on a suit-

able bracket or goose neck 3 which in turn is mounted on a table 4 of the frame 5 of the machine. The head 2 is here shown as carried at the front end of a yoke lever 6 which is pivoted between its ends at 7 to a standard 55 8 rising from the frame 5.

The buck 1 is overlaid with the usual compressible padding 9.

The actuating mechanism includes a toggle and means for successively straightening and boosting the toggle, and locking the toggle during the boosting operation. The boosting action is here illustrated as effected by lengthening one of the links of the toggle instead of boosting the entire toggle. 65

The means for operating the toggle is, preferably, power actuated, and as here illustrated the power means comprises an oscillating cylinder 10 having a piston movable therein, the rod 11 of which is connected to 70 the toggle mechanism to be presently described to successively straighten and boost the toggle during the closing operation of the press.

The cylinder 10 is in the machine here illustrated is arranged in nearly horizontal position and is pivoted at 12 to the frame. The cylinder is normally arranged inclined downwardly out of the horizontal and is movable into and slightly above the horizontal during 80 and closing of the press. The piston is single acting and the press is opened when the pressure in the cylinder is released by suitable countersprings 13. There are additional check springs as 14 which tend to momentarily retard the closing of the press or to overcome the momentum of the press head just prior to the time the head goes under final pressure. These springs 13, 14 are connected to the rear arm of the yoke lever 6. 85

The flow of motive fluid, as compressed air, to and from the cylinder 10 is effected by any suitable valve mechanism controlled by operator-operated means, as push buttons, one of which is illustrated at 15. The control 95 mechanism forms no part of this invention.

The piston rod 11 constitutes a reciprocating actuator for the toggle mechanism.

16 and 17 designate, respectively, the toggle links, these links being pivoted together 100

at 18 and the link 16 being pivoted at its outer or lower end 19 to the base of the frame, and the link 17 being pivoted to the rear arm of the yoke lever 6, as will be hereinafter described.

One of the toggle links preferably the link 17 comprises two members 17^a, 20 assembled to have relative endwise movement, the member 20 being movable endwise or extensible to boost the toggle or lengthen the link 17. The member 17^a is preferably tubular and the member 20 is preferably a rod slidably in the tubular member 17^a. The toggle is connected to the actuator 11 by connections which act to straighten the toggle or substantially straighten it depending upon the thickness of the work and the amount of compression of the padding 9.

The member 17^a of the link 17 is connected to the pivot pin 18 of the toggle to have a radial movement and in the illustrated embodiment of my invention, the member 17^a is formed with bifurcations 21 at its lower end between which the upper end of the link 16 extends, and the bifurcations are formed with lengthwise slots 22 in their lower ends in which bearing blocks 23 slide. The pivot pin 18 of the joint of the toggle extends through the upper end of the link 16 and is journaled in these bearing blocks 23. The sliding movement of the bearing blocks is resisted by suitable means, here illustrated as springs 24, located in the slots and thrusting against the upper sides of the bearing blocks. Thus the toggle links are pivoted together by a joint consisting of the pin 18 and bearing blocks 23 in slots 22 which permit longitudinal movement of one of the links, that is, the upper link member 17^a.

This longitudinal movement is normally prevented or resisted, until the head comes down onto the buck, by the springs 24, that is, there is no longitudinal movement until the toggle assumes any one of an indefinite number of substantially straightened positions, which occur when the head 2 comes down on the work on the buck 1 and begins to go under final pressure. The exact position of the toggle at such time will depend on the thickness of the work.

The relative radial movement of the links 16 and 17^a is primarily for the purpose of applying a locking force to lock the toggle in any one of an indefinite number of positions.

The locking means here shown has a friction or braking action. This locking means comprises braking surfaces in the form of grooves 25 provided in brackets 26 on opposite sides of the link 16 below the joint of the toggle and brake shoes 27 coacting with said surfaces, these brake shoes being provided at the lower ends of extensions 28 on the link member 17^a, these extensions 28 extending below the joint of the toggle. The

surfaces 25 and the brake shoes 27 are arc shaped and substantially concentric with the axis of the pivot pin 18 of the joint of the toggle. The brake shoes 27 are normally spaced apart from the brake surfaces 25 during the straightening of the toggle, and when the head 2 encounters sufficient resistance, the link member 17^a is moved downwardly longitudinally bringing the shoes 27 into coaction with the brake surfaces 25, thus locking the toggle in the position occupied at the time.

The upper end of the toggle member 17^a is pivoted to the rear arm of the yoke lever 6 to permit such radial movement and to also permit the boosting or longitudinal movement of the member or rod 20.

The yoke lever 6 is formed double in the usual manner or has its rear end formed with bifurcations 29 in which the pivot pin 30 connecting the link members 17^a, 20 is mounted. The upper end of the link member 17^a is formed with lengthwise longitudinal slots 31 through which the pivot pin 30 extends and the link member or rod 20 is formed with a pivot bearing 32 on the pin 30.

The slots 31 are shown as formed in bifurcations 33 in the upper end of the link member 17^a and the bearing 32 is shown as mounted between the bifurcations. The toggle is boosted or the link 17 extended by sliding the rod 20 and this boosting operation is effected by cam means carried by one of the links, preferably the link 17 and specifically the member 17^a thereof and coacting with the lower end of the rod 20.

34 designates a rotary scroll cam mounted upon a spindle 35 journaled in bearings 36 formed in the bifurcations 21 of the link member 17^a at a point spaced apart from the pivot 18 of the toggle. The cam coacts with a follower or roller 37 at the lower end of the rod 20.

The connections between the actuator or the piston rod 11 and the toggle serve to successively straighten the toggle and then rotate the shaft 35 to operate the cam to boost the toggle. These connections comprise a rock arm 38 mounted on one end of the spindle 35 and pivoted at 39 to the piston rod or actuator 11, the rock arm 38 extending at an angle to the piston rod or actuator 11.

Means is provided for normally locking the cam 34 from rocking while the toggle is straightening, this means being releasable automatically by the downward movement of the link member 17^a when the head 2 goes under pressure on the buck.

This means is shown as a detent 41, coacting with teeth 42 on the hub 43 of the cam 34, the detent being mounted on the joint or pivot 18 of the toggle and extending upwardly along one of the bifurcations of the link member 17^a and having a toothed end 44 engaging the teeth on the hub 43. Nor-

mally the detent is engaged with the teeth and hence prevents rotation of the cam shaft 35 and holds the arm 38 from pivotal movement so that said arm 38 and piston rod 11 act as a rigid unit during the closing of the press and the straightening of the toggle until the head 2 encounters the resistance of the buck, whereupon the toggle is momentarily subjected to compression while straightening and the link member 17^a is moved downwardly carrying the cam shaft 35 with it and the teeth on its hub out of engagement with the detent 41 or the hook-shaped end 44 thereof so that the cam shaft 35 is free to rock during further movement of the piston rod and boost the rod 20 to apply final heavy pressure and hence compensate for compression of the padding.

If the lift of the cam is steep enough the 20 detent feature may be omitted.

When the press is open, the parts occupy the positions shown in dotted center lines, Figure 1. When air is permitted to enter the cylinder 10 upon the depression of the 25 push button 15, the piston rod 11 moves outwardly and its motion is transmitted to the toggle through the rock arm 38 straightening the toggle. Evidently, no rocking of the shaft 35 occurs during the straightening of the toggle. As the toggle straightens and the head 2 comes down on the work into preliminary closed position and begins to compress the padding 9, the link member 17^a is moved downwardly longitudinally under the 30 reaction of the resistance offered to the head 2 and causes the pivot pin 30 to press against the lower ends of the slots 31. This downward movement causes the brake shoes 27 to engage the brake surfaces 25 and hold the toggle from further straightening movement. Thereupon the force of the piston rod 11 rocks the arm 38 into the broken line 35 position A and hence rocks the cam 34 causing the lift of the cam to boost the rod or the link member 20 upwardly, this upward movement pressing the pivot pin 30 towards the upper ends of the slots 31, thus further moving the head 2 until the resistance of the head is greater than the force of the cam 40 whereupon the movement of the piston rod 11 is stopped.

The press is held closed by the pressure against the piston and the air pressure is held in the cylinder as long as desired by any suitable valve means not necessary to describe.

The valves are released to release the pressure in the cylinder to permit the press to open by a suitable trip lever 40 not hereinbefore referred to.

Upon the release of the pressure in the cylinder, the reverse of the operation just described takes place, that is, the rock arm 38 first rocks the cam retrogradely out of its operated position or from the dotted line po-

sition A, Figure 1, and this movement permits the toggle to unlock, that is, the link member 17^a to move longitudinally under the influence of the springs 24 so that the toggle is unlocked and free to fold during the opening 70 of the press effected by the countersprings 13.

Insofar as this invention is concerned, the actuator 11 may be actuated by foot or any motor means and the motor may be controlled in any manner. The form of the motor and the control therefor does not enter into this invention.

What I claim is:

1. In a garment pressing machine, in combination, cooperative pressing elements, one of which is movable toward and from the other to open and close the press; actuating mechanism for the movable pressing element including a toggle; operating mechanism for said actuating mechanism; connecting means between the operating mechanism and the toggle to move the toggle toward straightened position and bring the movable pressing element into preliminary closed position; and means operated by said connecting 80 means, when the movable pressing element reaches preliminary closed position, to lengthen one of the links of the toggle and apply heavy pressure to the pressing elements. 85

2. In a garment pressing machine, in combination, cooperative pressing elements, one of which is movable toward and from the other to open and close the press; actuating mechanism for the movable pressing element including a toggle; operating mechanism for said actuating mechanism; connecting means between the operating mechanism and the toggle to move the toggle toward straightened position; and locking means, including a plurality of friction surfaces which are brought into contact by the connecting means when the movable pressing element encounters resistance, for frictionally locking the toggle in an indefinite number of substantially straightened positions. 100

3. In a garment pressing machine, in combination, cooperative pressing elements, one of which is movable toward and from the other to open and close the press; actuating mechanism for the movable pressing element including a toggle; operating mechanism for said actuating mechanism; connecting means between the operating mechanism and the toggle to move the toggle toward straightened position and move the movable pressing element into preliminary closed position; means, operated by the connecting means when the movable pressing element reaches preliminary closed position, for extending one link of the toggle to apply heavy pressure to the pressing elements; and locking means for holding the toggle against folding during the extension of the link. 115

4. In a pressing machine, a suitable frame; 120

- cooperating pressing elements, one of which is movable toward and from the other, means for actuating the movable element including a member connected to the movable element, a reciprocating actuator, a toggle comprising links pivoted together at their inner ends and pivoted at their outer ends respectively to the frame and to said member, one of the links including an extensible member operable to lengthen the link, connecting means between the reciprocating actuator and the toggle to straighten the toggle, and means to actuate the extensible member during the closing of the press.
5. In a pressing machine, a suitable frame, cooperating pressing elements, one of which is movable toward and from the other, means for actuating the movable element including a member connected to the movable element, a reciprocating actuator, a toggle comprising links pivoted together at their inner ends and pivoted at their outer ends respectively to the frame and to said member, one of the links including an extensible member operable to lengthen the link, movable cam means carried by one of the links and coacting with the said extensible member, and a connection between the actuator and the cam means.
6. In a pressing machine, a suitable frame; cooperating pressing elements, one of which is movable toward and from the other; means for actuating the movable element including a member connected to the movable element; a reciprocating actuator; a toggle comprising links pivoted together at their inner ends and pivoted at their outer ends respectively to the frame and to said member, one of the links including an extensible member operable to lengthen the link; movable cam means carried by one of the links and located in position to thrust said extensible member in a direction to lengthen the link; and a rock arm connected to the cam means to actuate it, said rock arm being pivoted to and arranged at an angle to the actuator.
7. In a pressing machine, a suitable frame, cooperating pressing elements, one of which is movable toward and from the other, means for actuating the movable element including a lever connected to the movable element, a reciprocating actuator, a toggle comprising links pivoted together at their inner ends and pivoted at their outer ends respectively to the frame and to said lever, one of the links including a member operable to lengthen the link, a rotatable cam carried by one of the links at a point spaced from the joint of the toggle and coacting with said member to lengthen the link, and a rock arm mounted concentric with the cam to rotate the cam, said rock arm being arranged at an angle to the actuator and pivoted thereto.
8. In a pressing machine, a suitable frame, cooperating pressing elements, one of which is movable toward and from the other, means

for actuating the movable element including a member connected to the movable element, a reciprocating actuator, a toggle comprising links pivoted together at their inner ends and pivoted at their outer ends respectively to the frame and to said member, one of the links including two members, one being movable with respect to the other to lengthen the two member links, movable cam means carried by one of the links and coacting with a member of the two member link and a connection between the actuator and the cam means, one of the toggle links having a movement relatively to the joint of the toggle, means for resisting said movement relative to the joint, and coacting locking elements carried by the toggle links respectively and operable into and out of locking position by the movement of the link member relative to the joint.

9. In a pressing machine, a suitable frame, cooperating pressing elements, one of which is movable toward and from the other, means for actuating the movable element including a member connected to the movable element, a reciprocating actuator; a toggle comprising links pivoted together at their inner ends and pivoted at their outer ends respectively to the frame and to said member, one of the links comprising two members movable with respect to one another, to lengthen the two member link, movable cam means carried by one of the members of the two member link and coacting with the other member of said two member link, a motion transmitting connection between the actuator and the cam means, and means operable by the movement of said connection relatively to the actuator to lock the toggle links in straightened position.

10. In a pressing machine, a suitable frame, cooperating pressing elements, one of which is movable toward and from the other, means for actuating the movable element including a member connected to the movable element, a reciprocating actuator, a toggle comprising links pivoted together at their inner ends and pivoted at their outer ends respectively to the frame and to said member, one of the links comprising two members, one being movable with respect to the other to lengthen the two member link, movable cam means carried by one of the links and coacting with a member of the two member link, a motion transmitting connection between the actuator and the cam means, and means operable by the movement of said connection relatively to the toggle to lock the toggle links in straightened position, and means for initially resisting relative movement of the said connection and the toggle until the toggle straightens.

11. In a pressing machine, cooperating pressing elements, one of which is movable toward and from the other, means for actuating the movable element including an ac-

tuator, a toggle connected to the movable element and connections between the actuator and the toggle to successively straighten and lock the toggle in any one of an indefinite number of substantially straightened positions; and means for initially resisting the locking operation until the toggle straightens.

12. In a pressing machine, a suitable frame, cooperating pressing elements, one of which is movable toward and from the other, means for actuating the movable element including a member connected to the movable element, a reciprocating actuator, a toggle comprising link members pivotally jointed together and pivoted respectively to the frame and to said member, the joint of the toggle including a connection permitting movement of one link member relatively to the other, and means for resisting such movement, one of said toggle link members being pivoted at its outer end to the part to which it is pivoted by a connection permitting movement and also including a rod member extending lengthwise thereof pivotally mounted on the pivot pin connecting said movable link member to said part, the rod member having a cam follower at its inner end, a cam rotatably mounted on one of the links and coacting with the follower, the cam having a rock arm, said rock arm being pivoted to the actuator and extending at an angle thereto.

13. In a pressing machine, a suitable frame, cooperating pressing elements, one of which is movable toward and from the other, means for actuating the movable element including a member connected to the movable element, a reciprocating actuator, a toggle comprising link members pivotally jointed together and pivoted respectively to the frame and to said member, the joint of the toggle including a connection permitting movement of one link member relatively to the other, and means for resisting such movement, the movable link member being pivoted at its outer end to the part to which it is pivoted by a connection permitting longitudinal movement, said movable link member also including a rod member extending lengthwise thereof and pivotally mounted on the pivot pin connecting said movable link member to said part, the rod member having a cam follower at its inner end, a cam rotatably mounted in the movable link member and coacting with the follower, the cam having a rock arm, said rock arm being pivoted to the actuator and extending at an angle thereto.

14. In a pressing machine, a suitable frame, cooperating pressing elements, one of which is movable toward and from the other, means for actuating the movable element including a member connected to the movable element, a reciprocating actuator, a toggle comprising links pivoted together forming the joint of the toggle and pivoted respectively to the

frame and to said member, the joint of the toggle including a connection permitting movement of one link relatively to the other, and means for resisting such relative movement, the movable link comprising two members, one of which is pivoted at its outer end to the part to which it is pivoted by a connection permitting longitudinal movement and the other member being a rod extending lengthwise of the first member and pivotally mounted on the pivot pin connecting said movable link member to said part, the rod having a cam follower at its inner end, a cam rotatably mounted on the movable link member and coacting with the follower, the cam having a rock arm, said rock arm being pivoted to the actuator and extending at an angle thereto, and a lock operated by the relative movement of the movable toggle link.

15. In a pressing machine cooperating pressing elements, one of which is movable toward and from the other, means for actuating the movable element comprising toggle links pivoted together by a joint permitting movement of one relatively to the other when the pressing elements initially engage, means for initially resisting such relative movement, means for effecting such relative movement, and means operated by the relative movement to hold the toggle links from further pivotal movement during the relative movement.

16. In a pressing machine, cooperating pressing elements, one of which is movable toward and from the other, means for actuating the movable element including an actuator, a toggle, and connections between the actuator and the toggle to successively straighten the toggle and extend the toggle during the closing of the press, said connections including two connecting booster parts, means for normally holding the booster parts from relative movement, means controlled by the resistance to straightening of the toggle when the movable element first applies pressure to the other element to release the holding means, and means to actuate the booster parts to extend the toggle when the holding means is released.

17. In a pressing machine, cooperating pressing elements, one of which is movable toward and from the other, means for actuating the movable element including an actuator, a toggle, connections between the actuator and the toggle to successively straighten and lock the toggle in any one of an indefinite number of substantially straightened positions, said connections including two coacting booster parts, means for normally holding the booster parts from relative movement, means controlled by the straightening and locking of the toggle to release the booster holding means, and means to actuate the booster parts to extend the toggle when the holding means is released.

18. In a pressing machine, a suitable frame,

cooperating pressing elements, one of which is movable toward and from the other, means for actuating the movable element including a member connected to the movable element, a reciprocating actuator, a toggle comprising links pivoted together at their inner ends and pivoted at their outer ends respectively to the frame and to said member, one of the links including a member operable to lengthen the link, a rotatable cam carried by one of the links at a point spaced from the joint of the toggle and coacting with said member, and a rock arm mounted concentric with the cam to rotate the cam, said rock arm being arranged at an angle to the actuator and pivoted thereto, and a lock normally holding the rock arm from rocking the cam, said lock being carried by the other link and normally coacting with the cam to hold it from rotation and operable to release the cam upon compression applied to the straightened toggle when the movable element first presses on the other element.

19. In a pressing machine, a suitable frame, cooperating pressing elements, one of which is movable toward and from the other, means for actuating the movable element including a member connected to the movable element, a reciprocating actuator, a toggle comprising link members pivotally jointed together and pivoted respectively to the frame and to said member, the joint of the toggle including a connection permitting movement of one link member relatively to the other, and means for resisting such relative movement, the movable link member being pivoted at its outer end to the part to which it is pivoted by a connection permitting longitudinal movement and also including a rod member extending lengthwise thereof pivotally mounted on the pivot pin connecting said radially movable link member to said part, the rod member having a cam follower at its inner end, a cam rotatably mounted in the movable link member and coacting with the follower, the cam having a rock arm, said rock arm being pivoted to the actuator and extending at an angle thereto, a member having teeth thereon associated with the cam, and a detent mounted on the joint of the toggle and having an engaging end normally coacting with said teeth, the teeth being movable out of engagement with the detent by the compression of the toggle when the movable element first applies pressure to the other element.

20. In a garment pressing machine in combination cooperative pressing elements, one of which is movable toward and from the other to open and close the press, actuating mechanism for the movable pressing element including a toggle, operating mechanism for said actuating mechanism, connecting means between the operating mechanism and the toggle to move the toggle toward straightened position, and means operated by said con-

necting means to extend the length of the toggle after it has moved toward straightened position.

In testimony whereof, I have hereunto signed my name, at Syracuse, in the county of Onondaga, and State of New York, this 18th day of April, 1929.

ERNEST DAVIS.
